UNITED STATES PATENT OFFICE.

WEBSTER C. ESTES, OF NEW YORK, N. Y.

DESIGN FOR A TURNED WOODEN BOX.

SPECIFICATION forming part of Design No. 32,120, dated January 23, 1900.

Application filed November 21, 1899. Serial No. 737,824. Term of patent 14 years.

To all whom it may concern:

Be it known that I, WEBSTER C. ESTES, a citizen of the United States, residing at New York, (Brooklyn,) in the county of Kings and State of New York, have invented and produced a new and original Design for a Turned Wooden Box, of which the following is a specification, reference being had to the accompanying drawings, in which—

Figure 1 is an elevation; Fig. 2, a plan, and Fig. 3 a vertical section.

The general configuration of the box in plan is round; and the leading features of my design consist in the conoidal surface subdivided by horizontal parallel approximately equidistant grooves, producing the effect of a surface composed of bands, and a deep semi-circular annular groove adjacent to the base of the box.

The design of the box comprises the co-

noidal surface *a* and the V-shaped horizontal grooves *b*, placed approximately at equal distances apart and dividing up the conoidal surface and producing the effect of bands of equal width.

Adjacent to the flat base *d* is a deep semi-circular annular groove *c*, and a flat band or bead *e* extends upward from the base to the annular groove *c*.

The respective parts of the box are separable 30 at one of the V-shaped grooves, as shown.

What I claim is—

The design for a turned wooden box, substantially as shown and described.

Signed by me this 18th day of November, 35 1899.

WEBSTER C. ESTES.
